UNITED STATES PATENT OFFICE.

ANDREW A. MUNRO, OF FLUSHING, NEW YORK.

DESIGN FOR A SEAT FOR BICYCLES.

SPECIFICATION forming part of Design No. 26,069, dated September 22, 1896.

Application filed June 29, 1896. Serial No. 597,477. Term of patent 7 years.

To all whom it may concern:

Be it known that I, ANDREW A. MUNRO, a citizen of the United States, residing at Flushing, in the county of Queens and State of New York, have invented and produced a new and original Design for Seats and Bicycle-Saddles; and I do hereby declare the following to be a full, clear, and exact description of the same, reference being had to the accompanying drawings, forming a part thereof, in which—

Figure 1 is a plan view of a seat or bicycle-saddle embodying the features of the design; and Figs. 2 and 3 are sectional views taken, respectively, upon the lines 2 2 and 3 3 in Fig. 1.

This design relates to seats, but more particularly to the seats of saddles used on bicycles, unicycles, tricycles, and like machines. The design consists in the contour or configuration of the seat, particularly in plan view. The upper marginal portion A of the seating-surface is approximately a plane surface, the top and sides being of irregular oval shape, terminating in front in a projection A'.

The leading feature of the design consists in the formation of the seating-surface within its marginal lines, in which openings B, having an approximate ovoid contour, are at each side of the center, back of the projection A', and the said seating-surface, adjacent to the walls of said openings, is tapered, presenting

concave rising walls. A depression or cavity C appears in the upper face of the projection A', extending back and merging into the surface D, dividing the openings B, which surface gradually descends from the cantle in direction of the pommel, and said surface D is quite narrow.

The essential feature of the design for the seat of a saddle is that of the unique anatomical formation of its upper or seat surface, which is briefly as follows: Greater permanent breadth of the broad portion of the said seating-surface; a rim or ridge on the outer edge of oval shape and of ample width to sustain the dense muscular tissues surrounding the upper portion of the pelvic bones; a gradual taper from these ridges to a depression terminating in an oval opening at each side, (into which the lower extremities of the ischial bones fit and hence do not come in contact with the seat,) from which it ascends and merges into an elevation or crest in the front of the cantle in the center, which portion in turn inclines downward and forward to a cavity extending to the front of the saddle.

I claim—

The design for a seat or saddle, substantially as herein shown and described.

ANDREW A. MUNRO.
